UNITED STATES PATENT OFFICE.

HARRY E. ROSE, OF COGAR, OKLAHOMA.

STEAK-POUNDER.

1,145,267.

Specification of Letters Patent.

Patented July 6, 1915.

Application filed December 12, 1914. Serial No. 876,934.

To all whom it may concern:

Be it known that I, HARRY E. Rose, a citizen of the United States, residing at Cogar, in the county of Caddo and State of Oklahoma, have invented new and useful Improvements in Steak-Pounders, of which the following is a specification.

The invention relates to an improved pounder constructed with a view to rendering tender and hence more desirable, steaks and the like.

The main object of the present invention is the provision of a pounder involving a sliding element in which the material to be treated is lead and rotary elements co-operating therewith to treat the material, the constructing involving means for holding the bones or the like so that they will be properly presented to the co-operating elements.

The invention in the preferred form of details will be described in the following specification, reference being had particularly to the accompanying drawings, in which:—

Figure 1 is a view in front elevation of the improved pounder. Fig. 2 is a side elevation of the same. Fig. 3 is a transverse section. Fig. 4 is a longitudinal section. Figs. 5, 6, and 7 are perspective details.

The improved pounder comprises a frame including uprights 1 connected at the lower end by a transverse brace strip 2, the uprights extending below the base strip and being provided with clamps 3, whereby the device may be secured to a suitable fixture. Secured to the uprights 1 and extending in spaced parallel relation are channel members 4 forming trackways.

Slidably mounted in the guideways 5 is an element 6 in the form of a platform having on its upper surface a series of material treating teeth 7, the element being herein-after referred to as the material platform.

The edges of the platform are provided with rollers 8 to slidably support the platform in movement in the trackway, the lower surface of the platform being further provided with spaced racks 9 designed to be connected by pinions 10 secured upon a shaft

11 mounted in the uprights 1, the shaft beyond one of the uprights being provided with a handle 12, whereby the platform may be reciprocated as desired.

Removably secured between the uprights is a supporting strip 13 provided at one edge

with eyes 14 to receive a rod 15 which seats at the respective ends in appropriate openings 16 in the uprights 1, the rod having a handle 17 to be engaged by a catch 18 to prevent disconnection of the rod. The opposing edge of the strip 13 is held in place by a bar 19 having tenon ends 20 to fit in the mortise 21 in the uprights 1, the bar having a recess 22 to receive a sliding catch 23 mounted upon the strip 13. By this means the strip is removably held in position between the uprights.

Depending from the strip 13 are spaced parallel bearing plates 24, in which are mounted the rotating elements of the pounder. These plates are arranged in pairs, one pair supporting each element, and the plates are of identical construction. Each plate has a lateral ledge 25 at its upper end, whereby it is bolted or otherwise secured to the strip 13, the plate depending from said ledge in approximately V-outline and being formed on the inner surface with upper and lower channels 26 and 27. These channels are in the nature of guiding grooves, upper one being of approximately U-form, and the lower one of V-form. The supporting flange 28 outlines the relatively lower or outer edge of each channel and the extreme upper part of the rear portion of each channel communicates with the lateral or rearwardly extending groove 29 which opens through the edge of the plate.

The pounding elements are in the form of disks or wheels, as 30, peripherally formed to provide teeth 31 similar to the teeth 7 on the platform 6. Each element 30 herein-after termed the pounding wheel, is supported in the carrier including a U-shaped frame 32 having the upper cross bar 33 extended beyond the depending side bars 34 and provided on such extended portion with rolling sleeves or rollers 35, as shown. The side bars 34 receive the axle projections 36 of the pounding wheel, and as thus assembled, the wheel is mounted between the plates 24 by engaging the rollers 35 in the channels 26 and the axle projections 36 in the channels 37, grooves 29 permitting ready insertion or removal of the supporting connection when desired. The channels 26 and 27 permit a play of the pounding wheels, against the tension of the spring 37 encircling rod 38 extending up from the cross bar 33 of the frame 32.

The strip 13 is formed with a longitudi-

nal slot 39, in which through the medium of the spring fasteners 40 is a removably secured holding strip 41 of the size to more or less accurately fit the slot. The strip 41 is formed with openings 42 to receive the upper ends of the rods 38, the construction providing for the convenient removability of any one or all of the pounding wheels, as will be apparent. The spring 37 is adjustably secured by having its upper terminal fixed to the nut 43 arranged to coöperate with the threaded thimble 44 through which the rod 38 passes, the thimble being removably secured to the strip 41, as shown.

15 In connection with the means for operating upon the material directly, I provide a means for properly placing the bones which may be with the material so that they will pass under the pounders without so retarding the travel of the material as to tear it from the bones. This bone placer includes supporting plates 45 secured to the frame and formed with vertically extending slots 46 in which is mounted a shaft 47 of the 20 corrugated or toothed roller 48, which is thus supported immediately above the platform 6 in advance of the pounding rollers. A shaft 49 is mounted in the supporting plates 45 above the roller, being provided at 25 one end with a crank 50 and connected with the roller shaft through links 51 pivotally connected to radial projections 52 of the shaft. By this means rotation of the shaft 49 will elevate the lower roller 48 with respect to the platform 6. The roller shaft is freely rotatable in one direction, being held against rotation in the opposite direction through the medium of a ratchet and dog 53.

30 The roller shaft may be rotated in any desirable manner, as for example as shown in Fig. 2, I have shown a hand lever 54 pivotally supported at its lower end at 55 and limited in play by strap 56, said lever being 35 connected by links 57 with the crank 50 of the shafts 49, whereby the desired movement may be imparted to the roller shaft, the throw of the lever causing rotation of the shaft.

40 The operation of the device will be fully apparent from the above description taken in connection with the drawings, it being obvious that material will be effectively treated in its passage through the pounder and that 45 any and all parts may be quickly removed for cleaning, renewal, or repair.

What is claimed is:—

1. A steak pounder including a frame, a

toothed platform mounted for reciprocation in the frame, means for operating the platform, a series of rotating pounding elements mounted above the platform, the rotating pounders being mounted for independent vertical movement, and a bone depressor mounted in advance of the pounding ele- 65

2. A steak pounder including a frame, a toothed platform mounted for reciprocation in the frame, means for operating the platform, a series of rotating pounding elements 70 mounted above the platform, supports in which said rotating pounders are independently mounted, and a bone depressor mounted in advance of the pounding element.

3. A steak pounder including a frame, a 75 toothed platform mounted for reciprocation in the frame, means for operating the platform, a series of rotating pounding elements mounted above the platform, and supports in which said rotating pounders are inde- 80 pendently mounted, each of said supports being formed with angularly related channels to receive the rotating pounders.

4. A steak pounder including a frame, a toothed platform mounted for reciprocation 85 in the frame, means for operating the platform, a series of rotating pounding elements mounted above the platform, supports formed with angularly related channels arranged in superimposed relation, a hanger 90 of inverted U-form having bearing rollers to engage the upper channel, said hanger receiving shafts of the rotating pounder, said shafts engaging the lower channels.

5. A steak pounder including a frame, a 95 toothed platform mounted for reciprocation in the frame, means for operating the platform, a series of rotating pounding elements mounted above the platform, and a bone depressor arranged in advance of the rotat- 100 ing pounders.

6. A steak pounder including a frame, a toothed platform mounted for reciprocation in the frame, means for operating the platform, a series of rotating pounding elements 105 mounted above the platform, and a bone depressor arranged in advance of the rotating pounders, said depressor comprising a rotating element, means for adjusting said element to and from the platform.

In testimony whereof I, affix my signature in presence of two witnesses.

HARRY E. ROSE.
